[57] **CLAIM**

The ornamental design for a tuner for satellite broadcast reception, as shown and described.

DESCRIPTION

FIG. 1 is a top, front and right side perspective view of a tuner for satellite broadcast reception showing my new design;

FIG. 2 is a front elevational view thereof;

FIG. 3 is a rear elevational view thereof;

FIG. 4 is a right side elevational view thereof, the left side being a mirror image of the right;

FIG. 5 is a top plan view thereof; and

FIG. 6 is a bottom plan view thereof.

The broken line showing on the display panel in FIG. 2 is for illustrative purposes only and forms no part of the claimed design.

FIG. 1

FIG. 2

FIG. 3
